UNITED STATES PATENT OFFICE.

ASHFORD C. DOWDEN, OF PINE BLUFF, ARKANSAS.

MATCH-SCRATCHER.

1,277,557.

Specification of Letters Patent.

Patented Sept. 3, 1918.

Application filed July 11, 1917. Serial No. 179,947.

To all whom it may concern:

Be it known that I, ASHFORD C. DOWDEN, a citizen of the United States, residing at Pine Bluff, in the county of Jefferson, State 5 of Arkansas, have invented certain new and useful Improvements in Match-Scratchers; and I do hereby declare the following to be a full, clear, and exact description of the invention, such as will enable other skilled 10 in the art to which it appertains to make and use the same.

This invention relates to improvements in match scratchers, and has for an object to provide a novelly constructed device of this 15 character which may be quickly and conveniently attached to and detached from an article of clothing such as the coat, vest, hat or the like.

With the above and other objects of similar nature in view, the invention consists in the construction, combination and arrangement of parts, set forth in and falling within the scope of the appended claim.

In the drawing:—

25 Fig. 1 is a front view of the device attached to a portion of a garment,

Fig. 2 is a longitudinal section therethrough,

Fig. 3 is a transverse section taken on the 30 line 3—3 of Fig. 1, and

Fig. 4 is a bottom plan view of the device detached from the garment.

Referring now more particularly to the accompanying drawing, there is shown a 35 portion of a garment A to which my improved match scratcher is removably applied and designated generally at B.

Specifically the scratcher consists of an elongated metal plate 5 having on its upper 40 side an abrasive surface 6 and further formed with a marginal flange 7. Soldered or otherwise secured to the underside of the plate adjacent one end are a pair of spaced parallel pin elements 8 the same between 45 their ends being bent as at 9 to extend in offset relation to the plate beyond the end thereof and being terminally sharpened as at 10. Also secured to the under side of the plate adjacent its other end are spaced pairs 50 of longitudinally alined guide rings 11 through which are slidably engaged a sec-

ond pair of pin elements 12 the same being also bent as at 13 between their ends to extend in offset relation to the plate and sharpened at their outer extremities. The inner 55 ends of the pin elements 12 are connected by means of a cross rod 14 the end of which projects beyond the plate 5 and are adapted to seat in recesses 15 provided in the flange 60 7 of the latter whereby to hold the elements 60 in extended position.

For limiting sliding movement of the pin elements 12 there are carried thereby lateral projections 16 which are disposed between the related guide rings 11 and abut the 65 same as the elements are extended or retracted with respect to the plate.

In use the device is applied to a garment as shown in Fig. 1, with the pin elements 8 penetrating the same. The pin elements 12 70 having been previously disposed in retracted position, they are now moved to extended position to also penetrate the garment, their movement being effected by engaging with the fingers the projecting ends of cross rod 75 and moving the same longitudinally of the plate until they enter the recesses 15 whereby to insure said pin elements against movement and consequent detachment of the device. 80

What I claim is:—

A device of the character described, comprising a concavo-convexed plate having an elongated flat center portion provided with a roughened outer surface, a pair of pins 85 fixed in the concaved side of the plate at one end thereof and projecting therefrom, a second pair of attaching pins slidably mounted in the concave portion of said plate to be projected beyond and retracted from 90 the opposite end of said plate, the side edges of said plate being formed with opposed notches, and a cross bar connecting the second pair of pins and engageable in the notches, the bar having its ends extended beyond opposite sides of the plate. 95

In testimony whereof, I affix my signature in the presence of two witnesses.

ASHFORD C. DOWDEN.

Witnesses:

G. R. HAWKINS,
C. A. NICKOLSON.
